LEAD PENCIL CONSTRUCTION

Charles Kosta, New York, N. Y.

Application May 3, 1935, Serial No. 19,544

1 Claim. (Cl. 120—19)

This invention relates to writing instruments and more particularly is directed to an improvement in refillable lead-pencil construction.

Among the objects of the invention is to improve lead-pencil constructions whereby few and simple parts are assembled to provide a neat appearing, conveniently proportioned writing instrument which shall be cheap to manufacture, and which shall be practical and efficient to a high degree in use.

Other objects of this invention will in part be obvious and in part hereinafter pointed out.

The invention accordingly consists in the features of construction, combinations of elements and arrangement of parts which will be exemplified in the constructions hereinafter described and of which the scope of application will be indicated in the following claim.

In the accompanying drawing, in which is shown various possible illustrative embodiments of this invention,

Figure 1 is a front elevational view of a lead-pencil construction embodying the invention;

Figure 2 is a fragmentary cross sectional view taken on line 2—2 in Figure 1;

Figures 3 and 4 are cross sectional views taken on lines 3—3 and 4—4, respectively, in Figure 2, and

Figure 5 is a perspective view of the lead pusher.

Referring in detail to the drawing, 10 denotes a lead-pencil construction embodying the invention which is seen to comprise an elongated body or holder 11, preferably made of wood or other suitable material of polyangular or circular cross sectional shape, a length of graphite, commonly called the "lead" 12 mounted for sliding movement through an axial bore 11a, the lead being positioned as a longitudinally extending core in said body 11.

The holder 11 may terminate at its leading end 11b in a tapered section, and if desired a reinforcing band 13 may be provided and located inwardly of said end section 11b. At the end of said holder 11 opposite said end section 11b, a ferrule 14 or other suitable thimble receptacle 14 is secured for retaining a rubber eraser 15, as shown in Figures 1 and 2.

Extending substantially the entire length of body 11 from the band 13 to the ferrule 14, there is provided a thin straight slot 16 which communicates with bore 11a. Mounted to slide with said bore 11a rearward of the lead 12 there is a pusher member 17 having a thin neck or shank 18 extending from one end thereof which passes through the slot 16, said shank 18 being termi-

nated at the exterior of the body 11 by an enlarged head or knob 19.

Said member 17, shank 18 and head 19 are preferably made of a single piece of metal and are adapted to abut the end of the lead 12 thus serving as a feeding means for projecting the latter through the body 11 as the lead end 12a is exposed beyond the end section 16 is used up in writing. A tightly fitting ring 20 is mounted on the exterior of the body for sliding movement therealong, said ring 20 serving as an adjustable stop for retaining said lead feeding means from being displaced while using the pencil 10. In order to facilitate the positioning of the ring 20 along the body 11, a rim ridge or outturned flange 20a is provided on said ring 20 which gives a convenient finger or nail grip means.

The pusher member 17 is preferably made sufficiently long, that is, the end 17a thereof is spaced from the shank 18, a distance which will propel the rear end of the lead 12b just short of the end section 16 of the body, thereby permitting practically the entire lead 12 to be available for use.

The utility of the improved lead-pencil construction will now be apparent. After constructing and assembling the pencil parts, as shown in the drawing, the pencil 10 may be used in the well understood manner. As the lead end 12a is worn down the knob 19 is pushed toward the leading end 10a which causes the member 17 to eject or propel the lead 12 out of the holder 11, until the desired length 12a thereof is exposed. The ring 20 is then moved until it abuts the knob 19 by means of contact made with the flange 20a, said knob 19 preferably being made wider than the width of the slot 16. In this position said lead feeding means and the lead 12 are retained against any tendency to back up into the holder 11.

By making the lead feeding means a single metal part, the shank 18 may be made relatively thin yet sufficiently strong to function satisfactorily and the slot 16 may be made correspondingly narrow to eliminate the possibility of foreign matter entering and clogging the movable parts of the pencil.

The proportion of the pencil body and parts constructed as above described and shown in the drawing form a well balanced writing means which is neat and attractive in appearance and convenient to handle.

It will thus be seen that there is provided a device in which the several objects of this invention are achieved and which are well adapted to meet the conditions of practical use.

As various possible embodiments might be made of the above invention, and as various changes might be made in the embodiment above set forth, it is to be understood that all matter herein set forth or shown in the accompanying drawing is to be interpreted as illustrative and not in a limiting sense.

Having thus described my invention, I claim as new and desire to secure by Letters Patent:

- 10 A pencil construction of the character described comprising a body having a tapered end and formed with an axial bore adapted to receive a lead slidably mounted therein, said body having a slot communicating with said bore extending lengthwise thereof and terminating short of said tapered end, a one-piece non-resilient

lead feeding means having a pusher member adapted to slide in said axial bore, said member being substantially the diameter of said lead, a relatively thin shank extending from said member and integrally formed therewith adapted to move in said slot, a knob of greater width than the shank integrally formed with and terminating the latter outside the body, said member having a length short of the distance between said terminal end of the slot and the tapered end of the pencil, and an adjustable ring slidably mounted on said body independent of said member adapted to be positioned in the path of movement of said knob to serve as an abutment stop.
